UNITED STATES PATENT OFFICE.

OTTO SCHEUERMANN, OF SHARON, PENNSYLVANIA.

AUTOMATIC ARCLESS PLUG CONNECTION.

Application filed August 31, 1925. Serial No. 53,760.

The invention relates to improvements in arcless plug connections using a switch in the plug circuit. The objects of the improvement are, first, to secure an absolutely arcless 5 plug connection; second, to eliminate the separate operation of a switch; third, to provide at all times currentless plug clips in an unconnected plug circuit; and fourth, to provide a compartment, containing all live parts in non- 10 service condition, accessible for purposes of repair.

The invention is illustrated in the accompanying drawing; in which: Fig. 1 is a vertical section through the device, mounted in 15 a box or in a convenient housing; Fig. 2 shows a bottom view with the housing removed; Fig. 3 is a vertical section of the plug.

The switch base 1 constitutes at the same 20 time the plug receptacle base. On the under- side of this base the entire mechanism of any type of reciprocating switch is mounted, in- cluding the switch clips 2, 2', 3, 3' and the switch blades 4, 4', 5, 5'; on the upper side of 25 said base, the plug-receptacle clips 6, 6' are mounted and connected through the base by screws 7, 7' with the respective switch clips 2, 2'. If the plug is not inserted these recep- 30 tacle clips 6, 6' are always currentless.

The advantage of the mounting of the 35 parts on both sides of the base 1 as described is, the creation of two separate compartments after the combination has been mounted in a convenient housing. The switch compart- 40 ment 8 and the plug receptacle compartment 9 can thus be entirely closed.

Live wire connections can be made in the 45 switch compartment only. It is impossible therefore to touch any current carrying part, except in repair cases, when the cover 10 on which the complete combination is mounted must be removed. To do away with the sepa- 50 rate switch operation, it is proposed to oper- ate the switch by inserting or extracting the 55 plug.

This is accomplished by a steep threaded 55 extension 12, on the switch stem 11, and the counterpiece, the "nut" 14 moulded in the plug bottom. As illustrated in Figure 3, a 60 small part 15, extending over the rim of the cover opening 16, engages in a groove 17 alongside of the plug. This groove 17 and the 65 extended piece 15 have the purpose to give the plug the accurate position on the one hand, and on the other to serve as a stop while in- 70 creasing the effect of the switch-operating

spring. The groove is lined with metal to lessen the friction.

If any plug connection is desired one sim- 60 plly pushes the plug in as usual. Before en- gaging the steep thread extension 12 with the nut 14, the plug blades 19, are already in contact with the plug clips 6, 6'. After moving the plug approximately $\frac{2}{3}$ of the thread ex- 65 tension's length (which corresponds to ap- proximately a 90° turn of the switch arbor 20) the switch will snap on and connect the plug circuit. The last third of the extension is easily passed by the plug, as no appreciable tensioning of the spring is necessary, and as 70 the natural impulse is to move the plug until it is stopped at the base 1.

Having pushed the plug all the way in 75 the nut will engage a small circular groove 21 and will be released, allowing the switch arbor 20 to move back again into the neutral position where the switch spring 21 is free of tension. In pulling out the plug, the action of the combination is reversed. At $\frac{2}{3}$ of the extension on the upward motion, the switch 80 snaps off and opens the plug circuit, before the plug blades 19 leave the plug clips 6, 6'. The plug then can be taken out without any 85 sparking effect at the contact clips. From the above description the operation of my de- vice will be entirely clear without further ex- 90 planation.

It will be understood, that I do not limit 95 myself to the exact details of construction shown and described but various modifica- 100 tions might be resorted to without departing from the spirit of the invention as set forth in the appended claims.

What I claim as my invention is:

1. In an automatic arcless plug connection 95 including a housing, a base in said housing separating the same into two compartments, plug receiving clips mounted in one of said compartments on one side of said base, and switch blades and clips in the other of said compartments on the opposite side of said base, means extending through the base connecting the plug clips and the switch clips, means for allowing the making of live wire connections in the part of said housing con- 100 taining the switch mechanism only, a means for operating the switch by the insertion of a plug, and a means for positively guiding the 105 plug.

2. In an automatic arcless plug connection, 110 a housing, a base in said housing dividing the same into two separate adjoining compart-

- ments, a cover for said housing, plug clips in one of said compartments on one side of said base, adapted to be engaged by the plug blades before the engagement with the switch, 5 a switch means in the other of said compartments, a switch stem, and an extension therefor having a steep thread and a circular groove, adapted to be received in said plug, a nut on said plug adapted to engage with 10 the steep thread on said extension to change the linear plug movement into a rotary one, said nut adapted to be released upon the engagement of the circular groove.
3. In an automatic arcless plug connection, 15 the combination of a housing having a cover and a nose on the same, with a plug having an inner groove adapted to be engaged by said nose for guiding said plug, a base dividing said housing into two separate compartments, plug connections and contacts in one 20 of said compartments, and switch connections and contacts in the other compartment, connections passing through said base for connecting the plug contacts and the switch contacts, said switch a double-pole switch, a 25 switch stem, an extension therefor having a thread and a circular groove, a nut on said plug adapted to engage the thread on said extension to change the linear plug movement into a rotary one and positively guiding said 30 plug, said nut and plug adapted to be disengaged from said stem upon the engagement of said nut with the circular groove.
- Signed at New York in the county of New York and State of New York this 1st day of June, A. D. 1925.

OTTO SCHEUERMANN.
